ADJUSTABLE DOOR HINGE

Hans Ulrik Hansen, 4208 Victoria Ave.,
Los Angeles, Calif.

Filed Oct. 11, 1956, Ser. No. 615,354

2 Claims. (Cl. 16—131)

This invention relates to a door-hinge of the butt type embodying a pair of leaf sections united by a pintle such as are commonly employed in hingedly mounting swinging doors in casings for horizontal swinging movement with one of the leaf sections countersunk in an edge of the door and the other leaf section countersunk in the jamb of the door casing, the invention more particularly pertaining to hinges of the above character embodying a means whereby the leaf sections thereof may be adjusted to compensate for sagging of the door with consequent misalignment with its casing.

Various constructions have heretofore been devised for embodiment in the leaf sections of a hinge whereby the sections may be adjusted on a door jamb to effect alignment of the door relative to its casing so as to avoid the use of shims as commonly employed for such purpose, but such constructions have not been standardized nor come into extensive use probably because of prohibitive cost of manufacture with consequent increase in selling price or cost to the consumer as compared with the costs incident to the common butt hinges now on the market.

The primary object of the invention is to provide an adjustable door-hinge for the purpose specified which is so formed as not to materially increase its cost of production relative to that of conventional non-adjustable hinges.

Another object is to provide a means for rendering the leaf sections of a hinge adjustable to vary the position of the hinge pintle laterally forward or back as occasion may require to vary the tilt of the door carried thereon relative to its casing, which means is of such character that it may be designed for application to a conventional hinge as an attachment thereto either under production or on-the-job, or which may be embodied as an integral part of the hinge in the course of manufacture thereof.

With the foregoing objects in view together with such other objects and advantages as may subsequently appear, the invention resides in the parts and in the combination, construction and arrangement of parts hereinafter described and claimed and as illustrated by way of example in the accompanying drawing in which:

Fig. 1 is an isometric view of a door-hinge showing the rear faces of the leaves thereof with the invention applied;

Fig. 2 is a view in cross section taken on the line 2—2 of Fig. 1;

Fig. 3 is an enlarged detail in section of one of the hinge leaf sections taken on the line 3—3 of Fig. 1, showing it as mounted on a jamb and depicting the manner of effecting adjustment thereof;

Fig. 4 is an isometric view of a modified form of the invention showing it as an embodiment of the hinge leaf section; and

Fig. 5 is an end view of the hinge shown in Fig. 4.

Referring to the drawings more specifically A—A indicates the pair of flat rectangular leaf sections of a hinge which sections are of equal thickness throughout and are pivotally connected together by a pintle B in the usual

2

manner. Each leaf section A is formed with screw receiving apertures here shown as three in number and embodying a single aperture C located intermediate the ends of the leaf section contiguous the outer margin thereof and also including a pair of apertures D—D spaced apart in alignment longitudinally of the leaf sections and located in inwardly and outwardly spaced relation to the aperture C. Manifestly the hinge leaf section may be equipped with any suitable number of screw receiving apertures but for adaptation to the present invention must essentially embody an arrangement of the apertures which will afford one or more apertures spaced relative to each other laterally of the leaf section.

The invention resides in providing the leaf section A with a single longitudinally extending narrow and shallow rib E protruding from the rear face of the section between the laterally offset apertures C—D, which rib is preferably arcuate in cross section to form a rocker when seated on the surface to which the leaf section is applied.

20 The rib E is characterized by having side margins which intersect the flat rear face constituting the underside of the leaf section, such side margins being spaced inwardly from the margins of the adjacent apertures C—D.

In the form of the invention shown in Figs. 1 to 3 the

25 rib is shown as comprising a strip 6 of suitable material preferably metal which strip is arcuate in cross section and has a flat under face which is seated on the underside of the leaf section and is securely engaged therewith in any suitable manner as by means of an adhesive. The strip 6, constituting a rocker, extends parallel with the longitudinal margins of the leaf section preferably throughout the length of the latter as shown in Fig. 1. This construction is advantageous in that it may be carried out either in the factory in producing the hinge as

30 an article of manufacture or it may be applied as an attachment to a conventional hinge, since a person of ordinary skill being supplied with the loose strip 6 may readily mount it on the leaf section.

In the form of the invention shown in Figs. 4 and 5

40 the rib E constitutes an arcuate protrusion 7 which is formed integral with the leaf section as by a stamping operation which construction is effected in the manufacture of the hinge.

In the application and operation of the invention the hinge is mounted in the usual manner, one of the leaf sections A being mounted on the edge of a door and the other leaf section being mounted on the door jamb with the leaf sections recessed and secured in place by the usual wood screws 8 and 9 screwed into the door jamb through the apertures C and D respectively.

50 In thus mounting a leaf section A the rocker rib E thereon will seat along its outer portion or ridge and between its side portions on the bottom 10 of the recess 11 in which the leaf section is mounted, as shown in Fig. 3, whereby the underside of the leaf section on opposite

55 sides of the rib E will be slightly spaced by the rib from the bottom of the recess and will normally be disposed in parallel relation thereto with the ends of the leaf sections abutting the ends of the recess.

60 In effecting alignment of the door with its casing, either when initially mounting the door or subsequent thereto, in event of sagging of the door such alignment is accomplished by tilting the leaf section A on the rocker rib E to laterally shift the axis of the pintle B either

65 rearwardly, as indicated by the dotted lines a in Fig. 3, or forwardly as indicated by the dotted lines b. This adjustment is effected by loosening the screw 8 and tightening the screws 9 to tilt the leaf rearwardly, as indicated by the dotted lines a or conversely by loosening the screws d and tightening the screw 8 to tilt the hinge leaf section A forwardly into the position indicated by

dotted lines *b*. In either event the previously loosened screw *8* or *9* is then tightened to seat on the hinge leaf to then co-operate with its companion screws to securely hold the leaf section stationary in its adjusted position. In some instances adjustment of either one or the other of the leaf sections may only be required to effect alignment of the door with its casing, but there may be occasions when it will be necessary to adjust both leaf sections.

In order to obviate or at least minimize objectionable projection of the outer face of the hinge leaf relative to the surface face of the door or casing leading from the margin of the recess *11* when the hinge leaf is mounted in the recess in a tilted position on the rib *E*, the combined thickness of the flat leaf *A* and the arcuate rib *E* at least approximates the depth of the recess, being preferably slightly less than and not exceeding such depth as indicated in Fig. 3. This arrangement is important since but very slight projection of the outer face of a hinge leaf of the type shown from the surface of the door or casing will form an abutment which will prevent closing of the door.

From the foregoing it will be seen that I have provided a very simple but highly effective means for adjusting the tilt of a hinge leaf section without the aid of shims and without materially increasing the cost of the hinge.

While a specific embodiment of the invention has been shown and described, the invention is not limited to the exact details of construction set forth, and the invention embraces such changes, modifications and equivalents of the parts and their formation and arrangement as come within the purview of the appended claims.

I claim:

1. In combination with a hinge supporting structure having a hinge-leaf receiving recess embodying a flat bot-

tom wall; a hinge including a leaf having a flat underside and having laterally off-set screw receiving apertures, a rib projecting from the underside of said leaf extending longitudinally intermediate the laterally offset apertures, said rib having opposed side margins intersecting the leaf in spaced relation to said apertures and having an outer margin seated directly on the bottom wall of said recess and then serving as a rocker on which the leaf may be tilted laterally in said recess to various positions, said leaf and rib having a combined thickness not exceeding the depth of said hinge leaf receiving recess, and screws extending through said apertures and engaging said leaf, said screws being directly engaged with the bottom wall of said recess contiguous the underside of the leaf and being tightened to hold said leaf against tilting on said rib.

2. A hinge leaf having a flat underside and of equal thickness throughout and having laterally offset screw receiving apertures, a single rib projecting from the underside of said leaf and extending longitudinally intermediate the laterally off-set apertures, said rib having opposed side margins intersecting the surface of the underside of the leaf in spaced relation to said apertures and having a transversely rounded outer margin for directly seating on the surface of a hinge supporting wall, said leaf being then tiltable to various positions relative to a supporting wall, and screws adapted to be engaged in said apertures and to be screwed directly into engagement with a supporting wall on which the leaf is mounted.
